(57) **CLAIM**

The ornamental design for a pet table, as shown and described.

DESCRIPTION

FIG. 1 is a front, right and top perspective view of a first embodiment of a pet table showing my design.

FIG. 2 is a rear, left and bottom perspective view of a first embodiment of a pet table showing my design.

FIG. 3 is a front elevation view thereof.

FIG. 4 is a rear elevation view thereof.

FIG. 5 is a left-side elevation view thereof.

FIG. 6 is a right-side elevation view thereof.

FIG. 7 is a top plan view thereof.

FIG. 8 is a bottom plan view thereof.

FIG. 9 is a front, right and top perspective view of a second embodiment of a pet table showing my design.

FIG. 10 is a rear, left and bottom perspective view of a second embodiment of a pet table showing my design.

FIG. 11 is a front, right and top perspective view of a third embodiment of a pet table showing my design; and,

FIG. 12 is a rear, left and bottom perspective view of a third embodiment of a pet table showing my design.

The broken lines are included for the purposes of illustrating portions of the pet table that form no part of the claimed design.

1 Claim, 12 Drawing Sheets
